APPLICATOR HEAD FOR LIQUIDS

Peter J. Van Loben Sels, 11838 Cherrylee Drive,
El Monte, Calif.

Filed May 3, 1965, Ser. No. 85,065

Term of patent 14 years

(Cl. D91—1)

FIGURE 1 is a perspective view of an applicator head for liquids, showing my new design;

FIGURE 2 is a front elevational view thereof;

FIGURE 3 is a top view thereof;

FIGURE 4 is a side elevational view thereof;

FIGURE 5 is a bottom view thereof; and

FIGURE 6 is a rear elevational view thereof.

The element shown in broken lines is a dispenser body member which is included for illustrative purposes and which does not form a part of the design.

The side opposite that shown in FIGURES 1 and 4 is a mirror image thereof.

I claim:

The ornamental design for an applicator head for liquids, as shown and described.
